Specification for Design.

Patented May 30, 1916.

Application filed November 29, 1915. Serial No. 64,177. Term of patent 3½ years.

To all whom it may concern:

Be it known that I, CHARLES E. DOUGLAS, a citizen of the United States of America, and resident of Cincinnati, county of Hamilton, State of Ohio, have invented a new, original, and ornamental Design for Floats, of which the following is a specification.

Figure 1 is a side view of a float showing my design. Fig. 2 is an end view of the float shown in Fig. 1.

Copies of this patent may be obtained for five cents each, by addressing the "Commissioner of Patents, Washington, D. C."

I claim:

The ornamental design for a float as shown.

In testimony whereof, I have hereunto subscribed my name this 26th day of November, 1915.

CHARLES E. DOUGLAS.
